(57) **CLAIM**

We claim the ornamental design for a contact lens, as shown and described.

DESCRIPTION

FIG. 1 is a perspective view of a contact lens, showing our new design.

FIG. 2 is a front elevation view of the contact lens.

FIG. 3 is a rear elevation view of the contact lens.

FIG. 4 is a right side elevation view of the contact lens.

FIG. 5 is a left side elevation view of the contact lens.

FIG. 6 is a top plan view of the contact lens.

FIG. 7 is a bottom plan view of the contact lens.

FIG. 8 is a perspective view of a second embodiment of the contact lens.

FIG. 9 is a front elevation view of a second embodiment of the contact lens.

FIG. 10 is a rear elevation view of a second embodiment of the contact lens.

FIG. 11 is a right side elevation view of a second embodiment of the contact lens.

FIG. 12 is a left side elevation view of a second embodiment of the contact lens.

FIG. 13 is a top plan view of a second embodiment of the contact lens; and,

FIG. 14 is a bottom plan view of a second embodiment of the contact lens.

The broken lines shown in the figures depict portions of the contact lens that form no part of the claimed design.

1 Claim, 8 Drawing Sheets
